UNITED STATES PATENT OFFICE

97,443

DESIGN FOR A TRAILER

James W. Small and Elmer W. Pahlke,
Chicago, Ill.

Application August 15, 1934, Serial No. 52,959

Term of patent 7 years

To all whom it may concern:

Be it known that we, James W. Small and Elmer W. Pahlke, citizens of the United States, residing at Chicago, in the county of Cook and State of Illinois, have invented a new, original, and ornamental Design for Trailers, of which the following is a specification, reference being had to the accompanying drawing, forming a part thereof.

The figure in the drawing represents a perspective view of the trailer looking toward one corner thereof.

We claim:

The ornamental design for a trailer substantially as shown.

JAMES W. SMALL.
ELMER W. PAHLKE.
